UNITED STATES PATENT OFFICE

LUTHER P. BROWN, OF CHICAGO, ILLINOIS.

BOX-MACHINE.

No. 899,506.

Specification of Letters Patent. Patented Sept. 29, 1908.

Application filed October 27, 1904. Serial No. 230,212.

To all whom it may concern:

Be it known that I, LUTHER P. BROWN, a citizen of the United States, and a resident of Chicago, in the county of Cook and State of Illinois, have invented certain new and useful Improvements in Box-Machines, of which the following is a full, clear, and exact description.

My invention relates to paper box making machines, and its object is to automatically feed, paper box blanks to the machine, to paste the longitudinal edges thereof, to fold over and cement said pasted edges to complete the box in its collapsed condition, and to deliver and stack said collapsed boxes in bundles containing a given number of the same. This I accomplish by the means hereinafter fully described, and as particularly pointed out in the claims.

In the drawings. Figure 1 is a side elevation of my improved paper box machine. Fig. 2 is a plan view of the same. Fig. 3 is a transverse vertical section taken on dotted line 3, 3, Fig. 2. Fig. 4 is a detail view showing the feed mechanism in perspective. Fig. 5 is a detail view showing in perspective one of the receiving boxes located at the delivery end of the machine. Fig. 6 is a detail view showing a conveying belt pulley in cross-section. Fig. 7 is a detail view showing the folding belt runway or track in cross-section. Fig. 8 is a perspective view of a portion of the folding belt, the runway on which it travels, and the former block used in connection therewith. Figs. 9 and 10 are detail views showing a plan and side elevation respectively of the guide shoes. Fig. 11 is a detail view showing a section of the folding-belt. Fig. 12 is a top plan view of one of the guide-shoes and rollers thereon, and Fig. 13 is a transverse section of a modified form of belt.

Referring to the drawings, A represents a suitable supporting frame for the machine embodying my invention. It is immaterial how this frame is constructed or supported so long as it forms a medium for properly assembling and enabling the operative parts of the machine to perform their proper functions. One end of this frame is provided with a semi-circular trough-shaped drop-frame α which connects the horizontal platform or bed of the main part of the machine with the alining end portion of said bed, adjacent to the end of the machine into which the box-blanks are fed. Journaled in suitable bearings, preferably beneath this end

portion of the bed, is a shaft which is provided with three or more wide pulleys, b , the periphery of which is concave or guttered to receive the conveying aprons B, B, substantially as shown in the drawings. These aprons connect the pulleys b , with corresponding pulleys c , journaled in suitable bearings depending from the under-side of the bed at the opposite end of the machine.

The upper stretch of the apron B extends in a perfectly horizontal plane from end to end of the machine, and in order to maintain the upper stretch of the apron in this horizontal position, I have provided the machine with longitudinal tracks C, which extend from the drop-frame α to which one end of the same is secured, to the opposite end of the machine.

In order to prevent the lateral displacement of the aprons B as they pass longitudinally over these tracks, I have provided the under surface of said aprons with a longitudinal cleat d of suitable flexible material, which is secured to and projects downwards from the central portion of the belt and enters a longitudinal groove e in said track, substantially as shown in Fig. 8 of the drawings.

One end of the shaft upon which pulleys b are secured extends through its bearings and is provided with a sprocket wheel D , which latter is connected by a suitable chain D' to the sprocket wheel D^2 secured to the extended journal of paste-roller D^3 which latter has bearings upon the upper edge of the paste receptacle E located in the trough of the frame α beneath the upper stretch of the apron B.

The aprons B are designed not only to convey the box-blank from the automatically feeding-hopper, but are also designed to fold over the longitudinal side edges of the box-blank as it moves through the machine, and cement the one edge of the same to the other edge. To accomplish this result, I provide the apron B midway its width with a continuous fly F, one side edge of which is secured in a suitable groove or otherwise to the center of width of the apron B. This fly F corresponds in width to one-half the width of the apron, and, until after the apron is moved past the trough-shaped drop-frame, the fly laps over the outer one-half of the apron B which is nearest the adjacent longitudinal side of the machine.

At a suitable point on the track C, after

the belt has traveled past the trough-shaped drop-frame *a*, said track has secured to its side edge an L-shaped arm *f*, which is, preferably made of a flat strip of metal, with one of the branches thereof riveted or otherwise secured to the outer side edge of the track *C*, and with the other or horizontal branch thereof extending over the aprons *B* between the fly and the upper surface thereof, so as to force the fly, as the belt moves forward, up, and to lift and turn it on its inner hinged edge by the former *G* until it is turned completely over and covers and laps against the inner half of the width of the apron *B*, *B*, farthest from the adjacent longitudinal side of the machine. The former *G* comprises a wooden block of suitable length which is arranged longitudinally over the half of the apron *B*, uncovered by the fly *F*. The base of this former *G* is but slightly above the upper surface of the apron *B*, and its edge adjacent to the outer longitudinal edge of the belt, enters the angle made by the seam which unites and secures the edge of the fly to the center of width of the belt, the longitudinal side of this former engaged by the fly, is inclined backwards or away from the same. When the apron passes beyond the arm *f* the fly is given a semi-circular turn, and the apron is kept so taut that when once the fly is given this turn it will continue to describe it at this point while the machine is in operation. The blank when it reaches the former *G* passes under the same and as the fly makes its half-turn, the longitudinal edges of the blank are turned upwards and the angle of the bend made by turning it upwards is defined by being brought in contact with the acute angle or edge of the former. When the longitudinal edges of the blank are thus folded over, the dimension of the blank is such that the margins of one edge of the folded portion will lap over the margins of the opposite folded edge of the blank, and be cemented thereto by the paste which was supplied to the under side of said lapping edges as it passes over the paste trough *E*. After leaving the former *G* the folded collapsed boxes pass under and between a series of compression-rollers *H*, which completes the cementing of the lapping edges of the box together. After leaving the last pair of compression-rollers, and before the delivery rollers *c* and *c'* of the machine are reached, the fly is turned back to its original position again so as to leave the folded collapsed box to be delivered straight out from and between said rollers *c*, *c'*. This is accomplished by a vertically disposed guide-roller *T* which is journaled to a suitable stud depending from an arm *t*, which is shown in the drawings as projecting from the bearings of the last series of rollers *H*. This roller *T* is located in such a plane that the fly will contact with it when in a vertical plane and will thereby be pre-

vented from returning to the position which it assumed upon leaving the former. The collapsed boxes are delivered from rollers *c* and *c'* to the lowermost of a series of boxes *h*, which are constructed substantially as shown in Fig. 5 of the drawings, and comprise a bottom, longitudinal sides and one end wall. The end of the box adjacent to the pulley *c* is omitted so that the collapsed boxes can be pushed into and enter the same as they pass out of the machine. At about the center of length of these receiving-boxes they are provided with suitable guide-plates *g* which have a vertical T-groove in them that engage a vertical tenon on the inner side of the standard *J*, and along the side of the guide-plates on one side of the boxes the latter are provided with a vertical rack *h'*. As the collapsed boxes are fed to the receiving boxes *h*, the latter moves downward by reason of the engagement of the rack *h'* by the pinion and when it passes out of engagement therewith, drops of its own weight upon a platform *X*, from which it can be removed by the operator one at a time as desired. The pinion *j* is secured on the end of a longitudinal spindle which is journaled in suitable bearings *k* at the base of the standard *J*, which spindle is actuated through the medium of the sprocket and chain connection *l* by the longitudinal shaft *K*, which latter has a mitered connection with the lowermost of the last pair of compression-rollers, *H*, substantially as shown in the drawings. These gears and the rack and pinion are so timed and correlated that the lowermost box *h* is released and drops to the platform *X* when say fifty of the finished boxes have been delivered. This forms a handy means for removing the finished boxes and at the same time furnish a reliable means for counting and keeping score of the number turned out by the machine.

The pulley *b* at the receiving end of the machine has a superimposed pulley *L* of less width, engaging it, which is mounted on the shaft *L'* that has bearings in blocks, that are depressed by coil-springs *m* placed in the vertical slots in the adjacent pendent end of the goose-necked portion of the superimposed frame *M* used in connection with the machine. These pulleys *L* have their periphery slightly concaved and are connected by a rubber belt to similar pulleys journaled in suitable bearings located at points on the opposite side of the trough-shaped drop-frame *a*, and together with pulleys *L* form a conveyor for urging forward the box-blanks to the folding devices of the machine. This superimposed portion *M* of the machine consists of two corresponding inverted U-shaped frames, the straight portions of which are bent at right angles to form supporting-feet therefor which are secured to the top or bed of the machine. Extending laterally from

each side of the top of this U-shaped frame are suitable brackets 2 and 3, the latter of which is extended in a horizontal plane a distance about equal to the width of the U-shaped supporting-frame and is turned downwards to form a goose-neck that extends nearly to the bed of the machine in the end of which is journaled the spring pressed roller L. At suitable points on the upper level stretch 10 of this horizontal portion there arise suitable standards or bearings in which are journaled sprocket wheels 4 and 5 that are connected by an endless chain 6. The latter sprocket derives motion from a pulley mounted on its shaft that is driven by the belt 7, connected to a suitable driving mechanism. On the opposite end of the shaft carrying sprocket wheel 5 is another sprocket wheel 8 that is connected by an endless chain 9 to a similar 15 sprocket journaled below the bed of the machine, and drives the gears and idlers that operate the series of rollers H, H. The other sprocket 4 has a sprocket on the opposite end of its shaft similar to sprocket 8 that 20 is connected by an endless chain 10 with a sprocket journaled just above the bed of the machine in the same vertical plane therewith, which latter sprocket in turn drives the roller N.

30 Pulley N is driven, preferably, by a sprocket and chain from an overhead source of power, and has its journal opposite said sprocket and chain extended through its bearings and provided with an arm N'. This 35 arm N' is connected by a rod n to and reciprocates the hopper O, which latter is a bottomless box of such dimensions from top to bottom as to hold the box-blank, and is preferably shaped like a rhombohedron with its 40 side nearest the pulley b of the machine inclined away from the same. The lower side edges of the hopper rest and slide back and forth upon a suitable track secured to the upper longitudinal edges of the side rails 45 connecting the upper ends of the legs of a table-frame P. The bottom of the hopper consists of a slatted endless belt p, or conveyor, which passes around pulleys q, q, secured to shafts journaled in bearings near 50 the tops of the legs of the table-frame at the ends thereof. The box-blanks placed in this hopper consist of a substantially rectangular piece of paste-board or thick paper, which are, preferably, kept bearing down upon the 55 slatted belt by means of the spring actuated depressing arms Q. As the said belt p moves the cross-slats thereof catch against the transverse rear edge of the blank and push it out from under the stack in the hopper to and between the rollers b and L. Belt p is actuated by connecting a sprocket x on the extended end of one of the journals of the pulley-shaft nearest the pulleys b, L, by means of an endless chain x', with a similar

sprocket y on the end of the extended journal of the idle-roller.

In order to retain the box-blank in its longitudinal course through the machine when its side edges are being folded over by the flies F of the outer conveying aprons B, B, I have provided a longitudinally arranged shoe R over the central apron B', which is provided on each side with a corresponding series of rubber faced rollers r, r, which latter are graduated in size from those at the end first engaged by the blank to those at the opposite end. These rollers all bear down on the apron B' on either side of the shoe. This shoe R is located midway between the formers, and the latter is likewise provided with a series of rollers S, which are journaled on suitable studs projecting from the side thereof nearest the shoe R. These rollers S are similar to those of shoe R, only less in diameter, and their rubber faced peripheries bear down upon the blank opposite the side of the former, against which the fly F of apron B is engaged in folding the sides of the blank, and remove the friction which would otherwise be created by the blank rubbing against the bottom of the formers, and at the same time assist in holding the blank straight to its longitudinal course while the sides of the blank are being folded.

In Fig. 13 I show a modified form of belt which is preferably made of two longitudinal sections Z, Z, and are attached to each other at their contiguous edges by a thin strip of leather or other suitable flexible material. 100 This belt may be substituted for the one shown in the drawings, but it has been found to be more advantageous to use the belt constructed similar to that shown in Fig. 11. However, I do not desire to be understood as 105 limited to either of the specific constructions shown.

The operation of my machine is as follows:—The blanks for the boxes having been previously cut in the desired shape are 110 placed in the hopper O at one end of the machine. The oscillations of this hopper by a pitman n causes the blanks to be fed one at a time under the receiving roller L and are guided between the straps and belts over the 115 glue reservoir where the revolving roller D' comes in contact with one edge of the blank. The blank now passes to the guiding-rollers S, S, r, r, and the fly on the apron B turns the edges of said blank one upon the other so 120 that the glued portion will come in contact with the opposite side edge of the blank. The folded blank now passes under the compression rollers H, H, and through the medium of rollers c, c' are fed into the boxes or 125 receptacles h.

What I claim as new is:

1. A paper box folding machine comprising an endless conveying apron, and an end-

less fly having one edge hinged longitudinally to said apron which folds over the outer surface of the apron and then returns again to its original position during a portion of the 5 cycle described thereby, means for folding said fly and means for returning the same to its original position.

2. A paper box folding machine comprising 10 a conveying apron having the half portion on one side of its center of width adapted to be folded over onto the other half of its outer surface during a portion of the cycle described thereby, a former engaged by said apron near the point where the apron makes 15 its fold, means for automatically folding said belt, and means for returning said belt to its original position.

3. A paper box folding machine comprising 20 an endless conveying apron one side edge of which is adapted to be folded transversely over onto the outer surface during a portion of the cycle described thereby, and a former engaged by said apron near the point where the apron commences its fold, and means for 25 folding said belt.

4. A paper box folding machine comprising 30 an endless conveying apron, and an endless fly having one edge hinged longitudinally to said apron which folds over the outer circumference of the apron and then returns again to its original position during a portion of the cycle described thereby, and a former engaged by said apron, near the point where said apron commences its fold, means for 35 folding said fly, and means for returning the same to its original position.

5. A paper box folding machine comprising 40 a conveying apron having the half portion on one side of its center of width adapted to be folded over onto the other half of its surface during a portion of the cycle described thereby, a former engaged by said apron near the point where the apron makes its fold, a friction wheel journaled to the side 45 of said former opposite the side engaged by the folding portion of the apron, and means for folding said belt.

6. A paper box folding machine comprising 50 an endless conveying apron one side edge of which is adapted to be folded transversely over onto the outer surface during a portion of the cycle described thereby, a former engaged by said apron near the point where the apron commences its fold, friction wheels 55 journaled to the side of said former opposite the folding portion of the apron, and means for folding said belt.

7. A paper box folding machine comprising 60 an endless conveying apron, an endless fly having one edge hinged longitudinally to said apron which folds over the outer surface of the apron and then returns again to its original position during a portion of the cycle described thereby, a former engaged by said

apron near the point where the apron begins its fold, having friction rollers journaled to the side thereof opposite the folding portion of the apron, means for folding said fly, and means for returning the same to its original position.

8. A paper box folding machine comprising parallel conveying aprons each having the half portion farthest from the other apron adapted to be automatically folded over onto the other half of the outer surface during a portion of the cycle described thereby, a shoe placed mediate said aprons, and means for automatically folding said belt.

9. A paper box folding machine comprising parallel conveying aprons each having the half portion of its width farthest from the other apron adapted to be folded over onto the other half of the outer surface during a portion of the cycle described thereby, formers engaged by said aprons near the point where the aprons make their fold, a shoe placed mediate said formers, and means for folding said belt.

10. A paper box folding machine comprising parallel endless conveying aprons the side edges of each of which farthest from the other aprons are adapted to be folded transversely over onto their outer surfaces during a portion of the cycle described thereby, formers engaged by said aprons near the point where the aprons make their fold, and having friction wheels journaled to the side thereof opposite that engaged by the folding portion of the aprons, a shoe placed mediate said formers, and means for folding said belt.

11. A paper box folding machine comprising parallel endless conveying aprons the side edges of each of which farthest from the other aprons are adapted to be folded transversely over onto their outer surfaces during a portion of the cycle described thereby, formers engaged by said aprons near the point where the aprons make their fold, and having friction wheels journaled to the side thereof opposite that engaged by the folding portion of the aprons, a shoe placed mediate said formers, and having friction rollers journaled to its sides, and means for folding said belt.

12. A paper box folding machine comprising parallel conveying aprons each having the half portion of its width farthest from the other apron adapted to be folded over onto the other half of the outer surface during a portion of the cycle described thereby, formers engaged by said aprons near the point where the aprons make their fold, a shoe placed mediate said formers and having friction wheels journaled to the sides thereof, and means for folding said belt.

13. A paper box folding machine comprising conveying aprons, one edge of each of which is adapted to be folded transversely

on to the opposite portion thereof and pasting mechanism adapted to paste portions of the box-blank, carried over the same by said aprons, and compression rollers between which said box blanks pass after being folded.

In testimony whereof I have hereunto set

my hand this 19th day of October, A. D., 1904.
